US00D783814S

(12) **United States Design Patent** (10) **Patent No.:** **US D783,814 S**
(45) **Date of Patent:** **** Apr. 11, 2017**

(54) **ADAPTER FOR FLATUS RELEASE**(71) Applicant: **B. Braun Medical SAS**,
Boulogne-Billancourt (FR)(72) Inventors: **David Hanuka**, Ramat-Yishai (IL);
Meir Or, Doar-Na Misgav (IL); **Refael Sommer**, Nesher (IL); **Tamir Shavit**, Doar-Na Galil MaAravi (IL)(73) Assignee: **B. Braun Medical SAS**,
Boulogne-Billancourt (FR)(**) Term: **14 Years**(21) Appl. No.: **29/493,019**(22) Filed: **Jun. 5, 2014**(30) **Foreign Application Priority Data**

Dec. 9, 2013 (IL) 54860
(51) **LOC (10) Cl.** **24-02**
(52) **U.S. Cl.**
USPC **D24/129**
(58) **Field of Classification Search**
USPC D24/127-131, 112-114, 133, 186, 118;

Clark & Elbing LLP

(57) **CLAIM**

The ornamental design for an adapter for flatus release, as shown.

DESCRIPTION

FIG. 1 is a rear elevation view of an adapter for flatus release showing our new design;

FIG. 2 is a perspective view thereof;

FIG. 3 is a right side elevation view thereof;

FIG. 4 is a top plan view thereof;

FIG. 5 is a front elevation view thereof;

FIG. 6 is a bottom plan view thereof; and,

FIG. 7 is a left side elevation view thereof.

The broken lines represent portions of the device that form no part of the claimed design.

1 Claim, 4 Drawing Sheets
